Attorneys:

UNITED STATES PATENT OFFICE.

LOUIS V. ARONSON, OF NEWARK, NEW JERSEY.

WHIRLIGIG.

Application filed March 30, 1923. Serial No. 628,802.

To all whom it may concern:

Be it known that I, LOUIS V. ARONSON, citizen of the United States, residing at Newark, in the county of Essex and State of New Jersey, have invented certain new and useful Improvements in Whirligigs, of which the following is a specification.

The invention relates to toys of the nature of the whirligig and has as an object the provision of a whirligig having an opening or openings and spark producing material adapted to provide sparks to show through said opening. By means of a covering of colored material upon the opening of one or more colors the sparks are caused to produce colored lights.

Illustrative embodiments of the invention are shown in the accompanying drawing in which:

20 Figure 1 is a face view of the whirling portion of the toy;

Figure 2 is a vertical section on line 2—2 of Figure 1;

Figure 3 is a face view, partly broken 25 away, of a modified form;

Figure 4 is a vertical transverse section partially in elevation upon the line 4—4 of Figure 3;

Figures 5 and 6 are face views of additional modifications;

Figure 7 is a rear view of the form of the device shown in Figures 3 and 4;

Figure 8 is a detail vertical section of a pyrophoric material holding device and Fig. 35 9 is a detail elevation of the end of the handle and its attachment to the rear of the driving means in the form of invention shown in Figs. 1 and 2.

The device as shown in Figures 1 and 2 40 comprises a revoluble disc (10), supported upon a stud bolt (11), mounted upon a handle (12), being secured thereto by a nut (13). The disc (10) is shown as formed integrally, or rigidly secured to, a sleeve (14) which 45 carries in rigid engagement therewith a pulley (15).

The pulley is shown as having a string (16) wound thereabout and having its end secured thereto by means of a knot (17). A 50 guide for the string (16) may be provided by means of striking a tongue (18) from the material of the handle, which tongue is perforated.

To support a band (19) of an abradant 55 material a ring (20) is shown as carried by members (21) mounted upon a transverse

member projecting laterally from the handle (12) which members (21) are turned at an angle to the transverse member and secured to the ring (20).

To produce sparks a piece of pyrophoric material (22) is caused to move over the abradant material (19). To hold the pyrophoric element there is shown a cylindrical socket (23) carried by the disc (10) and slotted to receive the end of spring (24) secured to the disc (10) as at (25) and which spring is adapted to cause pressure upon the pyrophoric element.

To make the sparks thus produced show 70 colored lights the disc (10) is shown as provided with a plurality of openings (26), two of which openings, those closely adjacent the socket (23), are preferably provided with a cover (27—28) of translucent colored material. It is desired to use red and blue coverings for the openings in this form of the device, and the remaining openings (26) which are left uncovered will show white lights as 75 the sparks appear opposite them.

To revolve the disc (10) the string (16) is wound fully upon the pulley (15); when a pull upon the string will cause a rapid whirling of the disc (10). The momentum of this motion when the string is unwound and immediately slackened will cause a rewinding of the string in the opposite direction in a well-known manner. The sparks produced will be thrown in a direction opposite from that of the revolution. Therefore, when the revolution is in a direction with the red covered opening (26) behind the pyrophoric element the sparks will be shown as red. When the revolution is in the opposite direction the sparks will show blue and at 80 all times some white sparks will appear. In the form of device shown in Figures 3 and 4 the disc (29) is shown as carried by a sleeve (30) which is provided with a pulley (31), the action of which disc and pulley is the same as that already described, a string (16) being provided to cause motion of the disc.

To carry a pyrophoric element a tongue (32) is shown as struck out from the material of the disc (29), and as having mounted thereon a socket (33) slotted for reception of a spring (34) to produce pressure upon the pyrophoric element (35). To produce sparks an annular ring (36) is shown as carried by a disc (37) and as bearing upon its exterior surface a band (38) of abradant material,

The disc (37) is shown as loosely mounted upon the bolt (39), and washer (40) being placed between the surface of the disc and the sleeve (30). With this arrangement of 5 parts the disc (37) will revolve slowly when the disc (29) is spun and the momentum of the disc (37) will cause such revolution to be much slower than that of the spinning disc, and the reversal of movement of the 10 disc (29) will insure the relative movement between the two so that sparks produced from the pyrophoric material will be shown through the openings (40) in the disc (37). It is preferred to cover openings (40) with 15 red, white and blue translucent material (41), or the white material may be omitted to allow the sparks in the natural color to show there-through. Preferably an opening (42) is left through which access may 20 be gained to the socket (33) for the purpose of renewing the pyrophoric material therein. A ball (43) is shown upon the end of the string (16) to be grasped by the user.

In the form of the device shown in Figures 3, 4 and 7, the material from which the handle (44) is formed, is cut to provide extending members (45, 46 and 47) the ends of which are bent at right angles to lie closely adjacent to the periphery of the pulley (31) as shown at (48) in Figure 4. These projections serve to prevent the string (16) from flying off the pulley.

In Figure 5 a form of the device is shown comprising a spinning disk (49) carrying a band (50) of abradant material. Mounted upon the bolt (51) upon which the disk (49) spins, there is shown an arm (52) carrying a socket (53) for holding abradant material, and a spring (54) for causing 40 pressure thereon. Projecting laterally from the arm there are shown rings (55-56) which carry coverings of translucent material (57) to provide the colored showing of the sparks produced by the pyrophoric element. The arm (52) being rigidly carried by the bolt (51) upon which the disk (49) freely spins, will remain stationary to cause relative movement between the abradant material and the pyrophoric element. 50 In Figure 6 is shown a still further modification in which a spinning disc (58) is shown provided with openings (59) some or all of which are provided with coverings (60) of varying color, and carrying a pyrophoric element holding device (61) of the form shown in detail of Figure 8.

As there shown the device comprises a cylinder (62) rigidly secured to the disc (58) and having a cap (63) against which a 60 spiral spring (64), carried within the cylinder, abuts, thus causing pressure upon the pyrophoric element (65).

The common feature in the various forms of the device is that there is a band of abra-

dant material, and a pyrophoric element 65 with means to cause one to revolve with relation to the other, and in addition an opening with a covering of colored material adjacent to the pyrophoric element through which the thus produced sparks may show as colored lights. Minor changes may be made in the physical embodiment of the invention without departing from its spirit. 70

I claim—

1. A whirligig comprising, in combination, a member having an opening, a covering of colored translucent material for said opening, a pyrophoric material holding device adjacent said opening, a circular band of abradant material, means to cause relative movement of revolution between said device and band whereby sparks may be produced to show through said colored material. 75

2. A whirligig comprising, in combination, a disc, a member mounted adjacent said disc, a band of abradant material upon one of said elements, a pyrophoric element upon the other of said elements, said pyrophoric element carrying-member having an 80 opening, a covering of translucent material for said opening whereby sparks produced by friction of said pyrophoric element will cause a show of colored lights, and means to spin said disc. 90

3. A whirligig comprising, in combination, a handle, a ring rigidly mounted upon said handle, a band of abradant material upon said ring, a disc revolubly mounted upon said handle adapted to spin in front of said ring, a pyrophoric element mounted upon said disc, said disc having an opening adjacent said element, and a covering of translucent material for said opening. 95

4. A whirligig comprising, in combination, a handle, a disc revolubly mounted on said handle, a pulley for causing revolution of said disc, members projecting from said handle closely adjacent to the periphery of said pulley, a ring mounted upon said handle, a band of abradant material carried by said ring, a pyrophoric element carried by said disc adapted to provide sparks by friction with said abradant element, said disc having an opening, and a covering of translucent material for said opening. 100

5. A whirligig comprising, in combination, a member having a plurality of openings, coverings of colored translucent material of differing appearances for some of said openings, a pyrophoric material holding device adjacent said openings, a circular band of abradant material, means to cause relative movement of revolution between said device and band whereby sparks may 110 be produced to show through said colored material. 115

LOUIS V. ARONSON.
